UNITED STATES PATENT OFFICE.

EMANUEL JACOBS, OF NEWBONE, MICHIGAN.

RAZOR-BLADE STROPPING AND HONING MACHINE.

1,090,986.

Specification of Letters Patent. Patented Mar. 24, 1914.

Application filed September 23, 1912. Serial No. 731,761.

To all whom it may concern.:

Be it known that I, EMANUEL JACOBS, a citizen of the United States of America, residing at Detroit, in the county of Wayne and State of Michigan, have invented certain new and useful Improvements in Razor-Blade Stropping and Honing Machines, of which the following is a specification, reference being had therein to the accompanying drawings.

This invention relates to a machine for stropping and honing razor blades and its object is to provide a simple construction which is efficient in its operation and will provide for the various necessary adjustments to bring the blade into proper relation with the stropping and honing devices.

A further object of the invention is to provide a machine which may be used to sharpen blades of ordinary razors or the detachable blades of safety razors and which has certain other new and useful features in the construction and arrangement of parts, all as hereinafter more fully described and pointed out in the appended claims reference being had to the accompanying drawings in which—

Figure 1 is a side elevation of a machine embodying the invention; Fig. 2 is a partial end elevation of the same; Fig. 3 is a vertical section on the line 3—3 of Fig. 2; Fig. 4 is a detail showing an elevation of a portion of the frame; Fig. 5 is a sectional detail on the line 5—5 of Fig. 4; Fig. 6 is a detail showing an end elevation of the cams and rolls; Fig. 7 is an enlarged sectional view through the blade carrying arm on the line 7—7 of Fig. 3; and Fig. 8 is a detail of the shifting arm.

As shown in the drawings a suitable supporting frame or post 1 is provided with laterally extending arms 2 at its lower end to embrace the edge of a table or other support and the lower arm is provided with a thumb screw 3 passing therethrough to engage the table and clamp the post in a vertical position. Fixed or non-rotatable shafts 4 are carried by the post and extend laterally therefrom in a horizontal position. One end of each of these shafts is fixed in a supporting disk 5 mounted in a cut away portion of the post between laterally extending arms 6 thereon through which arms pivot screws 7 extend vertically into the upper and lower edges of each disk in the vertical plane of the axis of the disk, to secure

the disks to the post and permit of their being turned upon the pivot screws 7 to swing the outer ends of the shafts 4 toward or from each other in a horizontal plane. 60 These supporting disks 5 are held in a common plane by means of screws 8 passing through the post and engaging screwthreaded openings in the disks.

Sleeved upon each of the shafts 4 adjacent to the disks 5 is a gear wheel 9, said gears intermeshing to transmit motion from one to the other, and one of the gears being engaged by a pinion 10 secured to the end of a crank shaft 11 mounted in a bearing 70 on the post and provided with a crank 12 at its outer end for turning the same.

Cam members 13 are secured to the gears 9 at the outer side thereof by means of screws or pins 14 (see Fig. 6), and sleeved upon 75 the shafts 4 adjacent to the cams 13 are suitable drums or rolls 15 each provided with a sheath or covering 16 of suitable abrasive material such as leather, and each roll is revolvably retained upon the shaft 4 by 80 thumb nuts 17 at the outer end of said shaft. The inner end of each roll is provided with a pin 18 to engage the adjacent cam 13 so that as motion is transmitted from the crank 12 through the pinion 10 and gears 9 to the 85 cams, said cams will come into engagement with the pins 18 and turn the rolls upon their shafts in opposite directions.

To support a razor blade 19 in proper relation to the rolls 15 so that they will engage the blade at the proper angle near its edge to sharpen the same, a supporting pin 20 is provided having a head 21 movable in a vertical slot 22 in the post. An adjusting screw 23 having a bearing in the post 95 extends longitudinally of the slot through a screwthreaded opening in the head and is provided with a knurled head 24 by means of which it may be turned to adjust the head vertically in the slot and raise or lower the 100 supporting pin, said pin being supported thereby in a horizontal position directly above the space between the two abrading rolls. A screwthreaded stud on the head 21 is engaged by a thumb nut 25 which in turn 105 engages the post 1 to clamp the head firmly in its slot in any position to which it is adjusted by the screw 23.

A blade holder comprising a tube 26 adapted to be sleeved upon the pin 20 and 110 to turn freely thereon, is provided with depending sprung jaws 27 between which the

razor blade 19 may be inserted with an endwise movement and will be firmly held by the spring of the jaws which engage the sides of the blades adjacent to the back thereof. Upon the inner end of the tube 26 is secured a depending arm 28 adjacent to the post with its lower end in the path of travel of the cams 13. This arm is split longitudinally inward from its lower end 10 and the severed parts are provided with oppositely inclined or beveled lower end faces 29 adapted to be engaged by said cams. One of the severed parts of the arm is provided with a screwthreaded opening to receive an adjusting screw 30 extending therethrough into engagement with the other part of the arm so that by turning the screw the halves of the arm may be sprung apart slightly. To detachably hold the blade 20 holder in place upon the pin 20 and to permit of a limited turning movement of said holder thereon, the tube 26 is formed with a slot 31 in its upper side extending transversely of the tube and a detachable pin 32 25 is provided to pass through the slot and into a transverse hole in the supporting pin. This pin 32 thus prevents the holder from sliding longitudinally upon the supporting pin, holding the arm 28 in the path of the 30 cams 13 and the slot 31 permits the free turning of the holder.

When the machine is used in sharpening a safety razor blade, the blade 33 is held within a blade holder or clip 34 formed of sheet metal with a rounded edge portion or back to fit within the spring clips 27 and firmly hold the thin metal blade in proper position for engagement with the rolls 15. This clip 34 may be made in any suitable 40 manner for firmly holding the blade and forms no part of this invention.

In operating the machine, the operator will remove the pin 32 and slip the blade holder from its supporting pin 20. The 45 blade 19 of the razor or the clip 34 with a safety razor blade engaged therein, may then be pushed endwise between the jaws 27 of the holder and the holder then reengaged with its supporting pin 20. The support is 50 then adjusted vertically by means of the screw 28 to bring the lower edge of the blade in the horizontal plane of the axes of the rolls 15. The blade may be tilted slightly between the jaws 27, said jaws being adapted 55 to yield, so that the lower edge of the blade will be parallel with the axes of the rolls and if the blade is worn away more at one end than at the other, the outer ends of the rolls may be moved toward or from each other 60 slightly by adjusting the bearing disks 5. A perfectly even contact may thus be secured between the blade and the rolls. After the blade has been properly positioned, the crank is turned and rotary motion is imparted 65 to the rolls. At the same time the cams

13 are alternately brought into engagement with the sides of the arm 28 and thus the blade holder with the blade in position therein is turned upon the supporting pin 20, first in one direction and then in the other to bring the edge of the blade into engagement first with one of the abrading rolls and then the other, the turning of the crank being continued until the blade is sharpened. The abrading sheath or cover for each roll 70 may be of a material which will act to hone the blade or of a material which will give a stropping action and if found desirable rolls with different abrading sheaths may be provided so that a pair of honing rolls may be taken off and a pair of stropping rolls put in their place. The swing of the blade holder may be increased or decreased by means of the screw 30 to give the desired contact between the blade and the rolls. 75

Obviously changes may be made in the construction and arrangement of parts without departing from the spirit of my invention and I do not limit myself to the particular form or arrangement shown. 80

Having thus fully described my invention what I claim is:—

1. A machine of the type described comprising a frame, disks pivoted in said frame and flush with the inner side thereof, shafts integral with said disks, abrading rolls detachably mounted on said shafts, means on said shafts between said disks and the inner ends of said rolls for imparting movement thereto, and a blade holder above the pass 95 between said rolls. 100

2. In a razor blade stropping and honing machine, a frame capable of being secured to a support, non-rotatable shafts having the ends thereof pivotally supported by said frame whereby the outer ends of said shafts can be swung in a horizontal plane, cams revolubly supported by said shafts, abrading rolls revolubly supported by said shafts and adapted to have movement imparted thereto 110 by said cams, a blade holder arranged above the pass of said rolls and adapted to support a razor blade in the pass of said rolls, means carried by said blade holder and actuated by the turning of the rolls for swinging the 115 holder to bring the blade alternately into contact with each of the rolls, and means carried by said frame for imparting movement to said cams. 120

3. In a razor blade stropping and honing machine, spaced parallel abrading rolls having inner ends thereof pivotally supported whereby the outer ends of said rolls can be swung in a horizontal plane, a blade holder extending longitudinally of said rolls, cams 125 at the inner ends of said rolls for simultaneously imparting movement to said rolls and to said blade holder, and a train of gears for imparting movement to said cams. 130

4. In a razor blade stropping and honing

machine, spaced abrading rolls having inner ends thereof pivotally supported whereby the outer ends of said rolls can be separated in a horizontal plane, means for locking said 5 rolls against lateral movement during the operation thereof, pins carried by said rolls, cams adapted to engage said pins and impart movement to said rolls, a blade holder pivotally supported above said rolls and 10 longitudinally of the pass thereof, and means for simultaneously imparting movement to said cams and to said blade holder whereby a blade held thereby is alternately brought into engagement with adjacent sides 15 of said rolls.

5. In a razor blade stropping and honing machine, spaced abrading rolls having inner ends thereof pivotally supported whereby the outer ends of said rolls can be separated 20 in a horizontal plane, cam members for imparting movement to said rolls, a blade holder, means for pivotally supporting said blade holder above the pass between the rolls, means for vertically adjusting said 25 blade holder relatively to the pass between said rolls, a depending arm carried by the blade holder and provided with adjustable means adapted to be engaged by said cams, and a train of gears for imparting movement 30 to said cams.

6. In a razor blade stropping and honing machine, a frame, pivoted disks carried thereby, non-rotatable shafts carried by said disks and capable of having the outer ends 35 thereof separated, abrading rolls revolvably mounted upon the said shafts, means for detachably holding the rolls thereon, an adjustable supporting pin carried by said frame, a blade holder pivotally mounted 40 upon said pin, and a depending arm provided with adjustable means extending adjacent to said rolls to be operated by the turning of said rolls to swing said holder and alternately bring a blade carried there- 45 by into engagement with adjacent sides of said rolls.

7. The combination with a frame, of non-rotatable shafts having inner ends thereof pivotally supported by said frame whereby 50 the outer ends of said shafts can be swung in a horizontal plane, means carried by said frame for locking said non-rotatable shafts in parallelism, abrading rolls revolvably mounted upon said shafts, revoluble cams

arranged upon said shafts between said rolls 55 and said frame adapted to impart movement to said rolls in opposite direction, a blade holder pivotally supported above the pass between said rolls, a depending arm carried by said blade holder and having adjustable means adapted to be engaged by 60 said cams whereby said blade holder is swung toward adjacent sides of said rolls, and means carried by said frame for imparting movement to said cams. 65

8. In a machine of the character described, the combination of a supporting post, supporting members pivotally attached to the post to turn upon a vertical axis, non-rotatable shafts fixed at one end to said supporting members and extending horizontally therefrom, means for adjusting and holding the supporting members in their adjusted positions to swing the free ends of the shafts toward and from each other, abrading rolls 70 upon the shafts, a blade holder pivotally supported in the vertical plane of the space between the rolls, and means for turning the rolls and swinging the holder. 75

9. In a machine of the character described, 80 the combination of a supporting post having a vertical slot at its upper end, non-rotatable shafts extending horizontally from one side of the post, intermeshing gears sleeved upon said shafts to turn freely thereon, cam members carried by said gears, abrading rolls sleeved upon the shafts and operatively engaging the cam members to be turned thereby, means for detachably holding the rolls upon the shafts, the supporting pin having 85 a head adjustable within the slot in the post and extending horizontally above the space between the rolls, means for adjusting the pin toward and from the rolls, a blade holder sleeved upon the pin and having 90 blade holding jaws depending therefrom, means for holding the blade holder upon the pin and permitting a free turning movement thereon, and a depending arm on the blade holder adapted to be engaged by the cam 95 members. 100

In testimony whereof I affix my signature in presence of two witnesses.

EMANUEL JACOBS.
